CHRISTIAN A. VOLF, JR., OF WEEHAWKEN, NEW JERSEY, ASSIGNOR TO MURRAY T. QUIGG, OF NEW YORK, N. Y.

RESONATING, MODULATING, AND PROJECTING OF SOUND ANIMATED BY ELECTRICAL MEANS

Application filed November 2, 1928. Serial No. 404,314.

This invention relates to sound resonating and sound projecting devices and more particularly to a resonating device of the uni-directional type particularly adapted for 5 use in auditoriums, theatres and the like, in which sound is to be projected or emitted from a stage or platform mainly in one general direction.

The present invention is an improvement 10 on the inventions illustrated and described in my applications Ser. No. 323,019, filed December 1, 1928, and Ser. No. 340,926, filed February 18, 1929, in both of which the sound 15 waves are directed on to the surface of a liquid and emitted substantially in every direction or, in other words, in the direction of all the points of the compass.

In the preferred form of the present invention sound waves which are set up by electrical means placed directly over an opening in the top of a container are directed against a board suspended within the container, the board supporting suitable resonating tubes. The sound waves are deflected 25 by the board, thereby setting up an echo, and the waves, together with the echo reinforcing and accompanying them, are resonated by the tubes and are discharged by the tubes upon a surface of water which vibrates in 30 harmony with the sound waves thus received upon its surface. The impact of the sound waves on the surface of the water sets up a second echo which reinforces and accompanies the waves of which it is an echo. The 35 waves so reinforced are carried by the vibration of the surface of the water along the surface of the water, remaining on the surface of the water to the margin most distant from the point of impact, at which point 40 they are discharged in a single direction. By the means which will be hereinafter more particularly described, undesired electrical and mechanical sounds known as "distortions" are prevented or inhibited, and the 45 desired vocal or other musical frequencies are resonated or modulated and are mingled and directed at a predetermined angle into an auditorium, whether indoors or outdoors, so that the sound vibrations are distributed 50 evenly to all parts of the auditorium, with-

out reverberation from the walls and without interference, clashing, or neutralization in mid-air of sound waves deflected from walls and other obstacles.

One object of my invention is to resonate 55 and modulate voice and other musical frequencies by means of air columns appropriate to the several frequencies in order to improve the quality of musical tones and human voice transmitted by electrical means, 60 whether from microphones, records or other sound producing means.

Another object of my invention is to mingle 65 different sound waves set up by simultaneous frequencies, thus preventing waves of low frequency from escaping into an auditorium at one angle to the auditors while the waves of high frequencies escape at another causing a predominance of low tones in one part 70 of the auditorium and high tones in another, as is the case with the horns and cones now generally in use, and by said mingling of simultaneous waves, assuring a proper blend 75 of sound waves simultaneously set up.

Another object of my invention is to cause 80 two predetermined echoes, each of which accompanies the sound of which it is an echo, thus reinforcing and clarifying the sound before it is discharged into the auditorium or atmosphere.

Another object of my invention is to cause 85 two predetermined echoes, each of which accompanies the sound of which it is an echo, before the sound is discharged into the auditorium in order to prevent uncontrolled echoes set up by the walls and obstacles within the auditorium which would cause distortion. It is known in the science of acoustics that the first and second deflections of a sound wave causes an echo, but at the third 90 angle of deflection no echo is set up and the sound wave is neutralized.

Another object of my invention is the projection or discharge of sound waves into an auditorium at a controlled angle in such a way that sound waves of varying length each move at the same angle from their common point of departure, or, in other words, all waves move in a path of the same character, thus preventing distortion set up by reso- 95 100

nance and reverberation of walls and obstacles and the neutralization of sound waves by the collision in mid-air of waves of the same pitch which have been deflected from opposite walls, which causes what are known as "dead spots".

Another object of my invention is the elimination in large measure of mechanical and electrical distortion inherent in sound reproduction by electrical means from the aggregate of sound waves before the said waves are discharged into the auditorium or atmosphere.

Various other objects of my invention will be apparent from the following detailed description of the preferred embodiment of the invention.

My invention is based upon the fact, among other things, that still water or other liquid with vibrating qualities approximating those of water, when employed in the manner described in the applications above referred to, vibrates in harmony with musical notes and tones of the human voice only, and by such vibration transmits sound to air in contact with its surface. Vibrations caused by waves of lower frequency penetrate to a varying depth, up to four inches, but all vibrations are most concentrated at the point of least depth. Thus sound waves of varying frequency striking water of a depth of four or more inches will vibrate the water and vibrations will animate and re-create identical sound waves at the margin of the water. If the margin of the water at one point is more shallow than at all the other points of the margin, the greatest intensity of vibration will occur at that point. It is known also that sound waves are transmitted, at least, by rolling over or passing over the surface of the water or other liquid outwardly as described in the applications above referred to, always seeking as a point of departure the margin of the liquid farthest from the point of original vibration.

The various features of my invention are illustrated in the accompanying drawings showing the invention in its preferred embodiment and a modification thereof in which:

Fig. 1 is a view in elevation, partly in section, of a device embodying my invention;

Fig. 2 is a cross-section on the line 2—2 of Fig. 1;

Fig. 3 is a detail of the structure of the tube board;

Fig. 4 is a view in perspective of the device shown in Fig. 1;

Fig. 5 is a detailed sectional view showing the container and the water tank;

Fig. 6 shows in perspective a modified form especially adapted for use out-of-doors; and

Fig. 7 is a view in elevation, partly sectional, of the device as shown in Fig. 6.

Referring more particularly to the drawings, the numeral 2 indicates a casing rectangular in shape and open at the lower end.

The casing is preferably made of heavy resonating material, such as five-ply wood veneer, free from knots or other imperfections. To the sides of the casing are preferably screwed triangular pieces 15, and thin blotting paper 15' is preferably inserted between the edges of the sides and the sides of the top where these are joined which serves to improve the resonating qualities of the casing. The pieces 15 reinforce the frame of the casing and give the interior of the casing a somewhat octagonal shape, consisting of four long sides and four short sides. The short sides resonate in harmony with the high frequencies and thus dispel the clash of such frequencies at sharp corners.

Three sides of the bottom of the casing are placed flush with three sides of the top of a liquid container 4. The liquid container is preferably made of, or lined with, glass, metal or other material adapted for holding water or other liquid without deterioration. One side of the liquid container protrudes beyond one side of the casing, and on this side the inside wall of the container forms an angle of less than 45 degrees with the floor of the container. The other sides of the container are at right angles with the floor thereof. The liquid employed in the container is preferably water, although any other liquid having the vibrating qualities of water may be used. The depth of the liquid in the container is 4 inches or more.

The sound waves may be generated by any instrument suitable for animating sound waves transmitted from a record, microphone or other similar device, and adequate for the use intended, the said instrument being no part of this invention. This device may be housed in a separate casing 6, the sound waves passing through a small amplifying cone or horn 8 serving to guide the sound waves to within the casing 2 through an aperture 3 of appropriate size in the top thereof whence they come in contact with and are deflected by a tube board 12. The tube board 12 supports a series of resonating tubes 10. Each tube is suspended in an opening corresponding to the size of the tube and held by means of a copper wire or ring 7, as shown in Fig. 2, for example, surrounding the tube above the board, forming a seat for the tube and holding it in the desired downward direction.

The board 12 is preferably made of non-resonant and non-absorbent material of sufficient thickness and strength to hold the weight of the desired number of tubes. A detail of the construction of the board is shown in Fig. 3, indicating two layers 20 of bakelite separated by a layer 21 of celotex and held firmly together by a bolt or clamp 22 at each of the four corners, to which is attached a ring 23 by which the board is

suspended from the top of the casing by chains 14.

The sound waves deflected by the board find their escape through the tubes, each 5 tube resonating the sound frequencies for which it is designed and adapted.

Mechanical and electrical noises set up by the generating means 6 or by distortion of sound which may occur in the casing are not 10 resonated and are dissipated by the resistance of casing and the tubes.

The sound waves emitted from the tubes vibrate the water, the lower frequencies vibrating the water to a depth of about 4 inches.

15 The vibrations are transmitted through the water to the points of least depth where the vibrations are most intense, namely, at the margin of the water on the side having the sloped interior 18. The intensity of the vibrations there communicate the vibrations to the air. The sound waves so set up, together with the sound waves which have rolled over the surface of the water, make their escape upon the lines of least resistance, namely, up 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 parent to those skilled in the art, without departing from the spirit or the scope of the invention as defined in the claims.

Having thus described my invention, what

is claimed as new is:—

1. A sound resonating and modulating device comprising a casing, sound generating means connected thereto, a plurality of tubes within said casing, a container for liquid positioned to receive sound waves from said tubes and a sound-emitting outlet communicating with the surface of said liquid so positioned as to emit sound waves outwardly in substantially a single direction. 70
2. A sound resonating and modulating device comprising a casing, sound generating means connected thereto, a plurality of tubes within said casing, a container for liquid positioned to receive sound waves from the said tubes and an angular outlet from said container for emitting sound waves in substantially a single direction within an angle of forty-five degrees with the horizontal. 75
3. A sound resonating and modulating device comprising a casing, sound generating means connected thereto, a plurality of tubes substantially vertically arranged within the casing and a container for liquid below the said tubes having an angularly disposed sound outlet for sending and projecting unidirectional sound waves in the desired path. 80
4. A sound resonating and modulating device comprising a resonating casing, sound generating means connected to the said casing, a series of resonating tubes mounted within said casing, said casing and tubes being adapted to resonate sound waves within the range of audible frequency, a container for liquid positioned to receive sound waves from the said tubes to cause vibration of the said liquid in response to the impinging sound waves and an angularly disposed outlet above the said liquid permitting sound waves emitted to travel outwardly therefrom in a single direction at an angle within forty-five degrees with the horizontal, thus permitting substantially all the energy of sound to be utilized in the desired direction for audition. 85
5. A sound resonating and modulating device comprising a resonating casing having interior corners, means for barring said corners to prevent interference or clashing of high frequency vibrations, a series of resonating tubes mounted within said casing, a container for liquid disposed below said tubes to receive sound waves therefrom, and an outlet having substantially parallel sides for emitting sound waves from above the surface of the liquid in substantially a single direction to permit substantially all the sound waves to be utilized for audition in the desired path. 90
6. A sound resonating and modulating device comprising a casing, a plurality of resonating tubes mounted therein to provide a plurality of air columns adapted to resonate appropriate sound frequencies, sound generating means associated with said casing to provide sound frequencies which may be resonated by the said air columns appropriate thereto, a liquid surface positioned to receive resonated waves from the said tubes and means to permit the escape of sound waves from the surface of the liquid in the desired direction for audition. 95
7. A sound resonating and modulating device comprising a casing, a plurality of resonating tubes mounted therein, sound generating means connected to the said casing, whereby the several frequencies set up by the sound generating means may be resonated by air columns in the appropriate resonating tubes, means for positioning a liquid beneath the tubes to receive the resonated waves from the said tubes, whereby the several frequencies of different sound waves simultaneously set up by the said sound generating means may mingle and blend on the surface of the liquid from which the frequencies or waves may be projected at the margin of the said liquid in a single predetermined direction. 100
8. A sound resonating and modulating device comprising a casing, a plurality of resonating tubes mounted within the casing, sound generating means connected to the said casing so as to cause frequencies set up by the sound generating means to be resonated by air columns in the appropriate resonating tubes, means for positioning a liquid below the said tubes to receive resonated waves therefrom, whereby sound generated by electrical and mechanical means accompanying the said frequencies may be dissipated by the dampening effect or resistance of the casing and the tubes to prevent the commonly called "distortion", and means to permit escape of the resonated sound waves from the surface of the liquid in a single predetermined direction for audition. 105
9. A sound resonating and modulating device comprising a casing, sound generating means connected therewith, a tube board and a plurality of tubes mounted thereon in the said casing, a liquid container positioned to receive sound waves set up by the sound generating means and resonated by said tubes, the said sound waves from the said sound generating means being deflected by the tube board and setting up predetermined echoes which accompany, clarify and reinforce the sound waves of which they are echoes, whereby the sound waves so reinforced are resonated by the tubes and projected upon the surface of the said liquid, the contact with the liquid setting up another predetermined echo accompanying, clarifying and reinforcing the sound wave of which it is the echo, and means for permitting projection of the sound waves thus reinforced into an auditorium in a single predetermined direction, 110
10. A sound resonating and modulating device comprising a casing, a plurality of resonating tubes mounted therein to provide a plurality of air columns adapted to resonate appropriate sound frequencies, sound generating means associated with said casing to provide sound frequencies which may be resonated by the said air columns appropriate thereto, a liquid surface positioned to receive resonated waves from the said tubes and means to permit the escape of sound waves from the surface of the liquid in the desired direction for audition. 115
11. A sound resonating and modulating device comprising a resonating casing having interior corners, means for barring said corners to prevent interference or clashing of high frequency vibrations, a series of resonating tubes mounted within said casing, a container for liquid disposed below said tubes to receive sound waves therefrom, and an outlet having substantially parallel sides for emitting sound waves from above the surface of the liquid in substantially a single direction to permit substantially all the sound waves to be utilized for audition in the desired path. 120
12. A sound resonating and modulating device comprising a casing, a plurality of resonating tubes mounted therein to provide a plurality of air columns adapted to resonate appropriate sound frequencies, sound generating means associated with said casing to provide sound frequencies which may be resonated by the said air columns appropriate thereto, a liquid surface positioned to receive resonated waves from the said tubes and means to permit the escape of sound waves from the surface of the liquid in the desired direction for audition. 125
13. A sound resonating and modulating device comprising a resonating casing having interior corners, means for barring said corners to prevent interference or clashing of high frequency vibrations, a series of resonating tubes mounted within said casing, a container for liquid disposed below said tubes to receive sound waves therefrom, and an outlet having substantially parallel sides for emitting sound waves from above the surface of the liquid in substantially a single direction to permit substantially all the sound waves to be utilized for audition in the desired path. 130

such sound waves being neutralized upon reaching the walls of the auditorium forming a third angle of deflection.

10. A sound resonating and modulating device comprising a casing, sound generating means associated with said casing adapted to set up sound frequencies within said casing, a board, a plurality of resonating tubes within said casing mounted substantially vertical therein upon said board, means for freely suspending the said board within the said casing to permit the vibration thereof, whereby musical frequencies are amplified and distortions or undesired frequencies are damped, 15 a container for liquid below the said tubes to receive sound waves transmitted by the resonating of the air columns within the tubes and an outlet from the said container adapted to emit sound waves in the desired path of 20 audition.

11. A sound resonating and modulating device comprising a casing rectangular in shape and open at the lower end, the sides of the casing having attached thereto triangular sections of material adapted to prevent distortion of sound within the casing, the positioning of the said triangular sections giving to the interior of the casing a modified octagonal form, and sound deadening means 25 between the abutting edges of the casing to improve the resonating qualities of the said casing.

12. A sound resonating and modulating device, comprising a casing, sound generating means in the upper part of the casing, a plurality of vertically disposed, open-ended resonating tubes positioned directly below said sound generating means, a container for liquid positioned directly below the lower 30 ends of the several resonating tubes, and a sound emitting outlet communicating with the surface of the liquid so as to emit resonated sound waves in substantially a single direction.

45 13. A sound resonating and modulating device, comprising a casing, sound generating means in the upper part of the casing, a plurality of vertically disposed, open-ended resonating tubes positioned directly below said sound generating means, a second sound generating means positioned in one of the side walls of the casing, for projecting sound waves directly outwardly therefrom, a container for liquid positioned directly below 50 the lower ends of the several resonating tubes, and a sound emitting outlet communicating with the surface of the liquid so as to emit resonated sound waves in substantially a single direction.

60 14. A sound resonating and modulating device comprising a casing, sound generating means in the upper part of the casing, a plurality of vertically disposed, open-ended resonating tubes positioned directly below said 65 sound generating means, a second sound gen-

erating means positioned in one side of said casing, a second set of vertically disposed, open-ended resonating tubes associated with said second sound generating means, a container for liquid positioned directly below the lower ends of the several resonating tubes, and a sound emitting outlet communicating with the surface of the liquid so as to emit resonated sound waves in substantially a single direction.

70 15. A sound resonating and modulating device, comprising a casing, sound generating means in the upper part of the casing, a plurality of vertically disposed, open-ended resonating tubes positioned directly below said sound generating means, a second sound generating means positioned in one side of said casing, a second set of vertically disposed, open-ended resonating tubes associated with said second sound generating means, said second sound generating means serving to project sound waves into said second set of resonating tubes, and also laterally and directly outwardly of the casing, a container for liquid positioned directly below the lower ends of the several resonating tubes, and a sound emitting outlet communicating with the surface of the liquid so as to emit resonated sound waves in substantially a single direction.

75 80 85 90 95 In testimony whereof I have affixed my signature.

CHRISTIAN A. VOLF, JR.
